UNITED STATES PATENT OFFICE

2,549,980

TOY HANDCAR

Henry Machesney, Brentwood, Pa.

Application February 26, 1949, Serial No. 78,549

1. Claim. (Cl. 46—107)

This invention relates to a mechanical toy, and important objects and advantages thereof are to provide a toy of the character described, which comprises a miniature hand car generally representative of the conventional type of small, hand propelled car used by railroad laborers, which includes a rocking beam actuated by the rotation of the wheels thereof, and which embodies a pair of manikin figures with shiftable parts allowing the pumping action of the latter to simulate the actual propulsion of the hand car by such movement of the manikin figures.

Further objects of the invention are to provide a colorful toy of the class stated, which operates to visibly display considerable action and mechanical movements, and consequently will afford much entertainment, amusement and fascination to children as a plaything, which is simple in its construction and arrangement, durable, attractive in appearance, positive in its action, and comparatively economical in its manufacture.

With the foregoing and other objects in view which will appear as the description proceeds, the invention resides in the novel construction, combination and arrangement of parts herein specifically described and illustrated in the accompanying drawing, but it is to be understood that changes in the form, proportions and details of construction may be resorted to that come within the scope of the claim hereunto appended.

In the drawing wherein like numerals of reference designate corresponding parts throughout the several views:

Figure 1 is a side elevational view of a toy hand car constructed in accordance with the invention.

Figure 2 is a top plan view thereof.

Figure 3 is an enlarged side elevational view 40 of the spring drive mechanism embodied in the invention.

Figure 4 is a side elevational view of a modified form of the invention.

Referring in detail to the drawing, the toy hand car comprises an oblong, rectangularly-shaped platform frame 1. The frame is generally flat and disposed horizontally, and includes a pair of integrally formed side flanges 2, which depend at right-angles at respective side edges of the frame and extend throughout the length of the latter. The end portions of the flanges are tapered, as indicated at 3, to enhance the appearance of the frame structure.

A straight shaft 4 and a crank shaft 5 are 55

suitably journaled for rotation in the side flanges 2 of the frame 1, and extend transversely in the latter in spaced relation to each other. A pair of opposed wheels 6 are fixed on respective ends of the straight shaft 4, and a similar pair of opposed wheels 7 are fixed on respective ends of the crankshaft 5.

The wheels 6 and 7 are disposed inwardly of the side flanges 2, and project a considerable distance above the frame 1 through respective slots 8, 9, 10 and 11, which are provided therefor in the frame. The wheels are of a considerable diameter to enhance the mechanical activity of the device.

15 A tapering, hollow standard 12 is fixed in position on the frame 1, and projects vertically upward from the latter. The standard is oblong, rectangularly-shaped in transverse cross section and is disposed longitudinally on the center of the frame.

An elongated, longitudinally extending rocking beam 13 is supported, centrally of its length, on the standard 12, and is formed with a centrally disposed looped portion 14, which surrounds the reduced upper end of the standard. A rocking rod 15, journaled for rocking movement, extends transversely through the reduced upper end of the standard, and has its ends fixed in the respective sides of the looped portion 14 of the beam, whereby the latter is allowed a seesaw or oscillating movement on its connection with the upper reduced end of the standard.

20 A rocker arm 16, having its upper end fixed to the rocking rod 15, depends at right angles to the rocking beam 13 and extends through the standard 12. The lower end of the rocker arm is pivotally joined to one end of a connecting bar 17, which latter has its other end pivotally connected with the crankshaft 5. It will be obvious that, during the travel of the hand car, the rotation of the wheels 7 will impart rotation to the crankshaft and thereby actuate the connecting bar, the rocker arm, and the rocking rod to impart seesaw oscillating movement to the rocking beam 13. The side walls of the standard are preferably provided with large openings 18, so that the movement of the rocker arm is clearly visible during the operation or travel of the hand car.

25 A short cross bar 19 is fixed in each end of the rocking beam 13. A pair of articulated manikin figures, respectively indicated at 20 and 21, are secured to the upright position on respective ends of the frame 1. The manikin

figures face each other and are joined at their waistlines 22, and the hand members thereof are pivotally joined, as indicated at 23, to respective ends of the cross bars. It will be apparent that the seesaw oscillating movement of the rocking beam will impart an alternating stooping and straightening movement to the upper portions of the manikin figures, whereby the latter will appear as actually effecting the operation of the rocking beam and of the hand car itself. It will here be noted that the position of the arm portions of the manikin figures 29 and 21 are varied with respect to each other, for the purpose of somewhat varying the relative movements of said manikin figures to thereby provide greater operating variety of movement.

The toy hand car is provided with a spring drive mechanism 24, which may be of any suitable construction and carried by the frame 1. The drive mechanism is of the type adapted to be rewound by means of a key 25 in the conventional manner well known in the art.

The drive mechanism 24 includes a driving gear 26, which meshes with a gear 27 that is fixed on the straight shaft 4. The operation of the drive mechanism will propel the hand car and, of course, thereby cause the actuation of all other movable parts of the device. A suitable control element 28 is pivotally mounted on the frame 1, and is operable to engage the gear 27 to suspend the operation of the drive mechanism when desired. A hitching link 29 is pivotally connected at one end of the frame 1 to allow the attachment of other types of toy cars with the improved hand car.

The disclosure, shown in Figure 4, comprises a hand car consisting of a platform frame 30 mounted on flanged wheels 31 to adapt the latter for travel on the conventional type of toy track rails 32. An electric motor 33, of any suitable construction, is mounted on the frame 30, and operates a drive mechanism 36 to propel the hand car. A rocking beam 34 is connected, centrally of its length, to the motor by a pivoting pin 35. A connecting bar 37 is pivotally connected to the rocking beam 34 and to one of the wheels 31 to impart seesaw oscillating movement to the rocking beam 34 during the driven travel of the hand car. A manikin figure, of the type above-described, is connected at each end of the rocking beam 34.

It is apparent that the toy hand car may be constructed without any drive mechanism and be operated by being towed by hand, and that such

non-powered device may be provided with flanged wheels to adapt same for being coupled in train of toy cars upon track rails. Further, the power-operated type of hand car may be employed to 5 propel itself or to haul a train of toy cars attached therewith.

The present invention provides a most durable and mechanically active toy of its kind, which may be colorfully and attractively decorated, and 10 successfully employed as a plaything for the amusement and entertainment of children, and in which the embodied manikin figures are of considerable width and thickness.

What I claim is:

15 A toy hand car of the class described, comprising the combination of a platform frame, a pair of spaced shafts journaled for rotation in said frame, one of said shafts being formed with a centrally disposed crankshaft, a wheel fixed on each end of said shafts, a hollow standard secured on the center of said frame and tapering toward the upper end thereof, a rocking beam including a looped rectangularly-shaped center portion, said center portion surrounding the reduced upper 20 end of said standard, a transversely extending rocking rod pivotally engaged in said standard and having the ends thereof fixed in the center of respective sides of said looped center portion to allow the seesaw oscillating movement of said 25 beam, a rocker arm having its upper end fixed to said rod and depending through said standard and through said platform, a connecting bar pivotally connected with the lower end of said arm below said platform and with said crankshaft, and a pair of manikin figures including 30 arms mounted on said frame and being pivotally joined with respective ends of said rocking beam, the upper portions of said manikin figures being pivotally connected with respective lower portions 35 thereof, the arm extensions of one of said upper portions varying from the arm extensions of the other of said upper portions to vary the movements of said upper portions with respect to each other.

45 HENRY MACHESNEY.
